Primary Examiner — Barbara Fox*Assistant Examiner* — Mehri F Bajoul(74) *Attorney, Agent, or Firm* — Novick, Kim & Lee, PLLC; Sang Ho Lee(57) **CLAIM**

We claim the ornamental design for a container for cosmetics, as shown and described.

DESCRIPTION

FIG. 1 is a perspective view of a container for cosmetics, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the drawings depict portions of the container for cosmetics that form no part of the claimed design.

1 Claim, 4 Drawing Sheets(56)
